GARMENT HANGER

Albert B. Tammen, Floral Park, N. Y.

Application May 10, 1937, Serial No. 141,762

2 Claims. (CL. 223—96)

The present invention relates to new and useful improvements in garment hangers of the coat and trouser type.

The primary object of the invention is to provide a garment hanger that will support and retain the shape of a coat with added means for retaining and gripping the cuff of trousers suspended from the hanger.

A further object is to provide a garment hanger whereby the trousers are suspended by engagement of the cuff ends between a pair of clamping members, said members being so designed as to extend inwardly to form an added supporting feature.

The invention will be fully and comprehensively understood from a consideration of the following detailed description when read in connection with the accompanying drawing which forms part of the application.

20 In the drawing:

Fig. 1 is a top plan view of one embodiment of the invention.

Fig. 2 is a side elevational view illustrating the coat and trousers hanger in its preferred form.

25 Fig. 3 is a longitudinal sectional view taken substantially on line 3—3 of Fig. 2.

Fig. 4 is an end view of the hanger illustrated in Fig. 2, taken on line 4—4 of Fig. 2.

Fig. 5 is a front elevational view of a modified form of the invention.

30 Fig. 6 is a sectional view taken substantially on line 6—6 of Fig. 5.

Fig. 7 is a front elevational view of a second modified form of the invention; and

35 Fig. 8 is an end elevation of the hanger illustrated in Fig. 7.

Referring to the drawing for a more detailed description thereof, the hanger illustrated in Figs. 1 and 2 comprises a pair of arms 10 and 11 for supporting the shoulder portions of a coat in the usual manner. By referring to Fig. 1 it will be noted that each arm 10 and 11 is formed of a single strip of wire or similar material forming looped portions 12 at the outer ends thereof

40 and reduced looped portions 13 at the inner ends. The free ends of the wire are twisted or coiled at 14. The looped portions 13 are swingably mounted by engagement in the loops 15 formed integral with the cross member 16 and within said member is a central loop 17 from which extends a suspending hook 18. Referring to Fig. 2, it will be noted that the free ends of the member 16 are twisted about the depending members 19 and the free ends 20 thereof are bent

45 for engagement with the reduced ends of the arms 10 and 11. When the ends 20 are in engagement with the reduced ends of the arms 10 and 11 said arms are frictionally held in latched position but by exerting an upward pull on each of the arms the same are adapted to be readily 5 disengaged for swinging upwardly, at which time they will pivot about the loops 15. The upward movement of the arms 10 and 11 is occasionally necessary when positioning the trousers within their supporting means, to be later described.

10 As aforeindicated, a pair of arms 19 are suspended from the member 16 and said arms support the trousers hanger indicated generally by the numeral 21. By referring to Fig. 4 it will be noted that the arms 19 are substantially 15 U-shaped and the free ends thereof support the trouser hanger 21. The hanger 21 is preferably formed of two parts and includes complementary frame members 22 and 23, said frame members being substantially rectangular shaped and having a plurality of transverse bars 24 forming a part thereof. In the preferred form of the invention the frame and bars are formed of wire and said bars may be attached to the frame by any desired means such as soldering or the like.

20 Referring to Fig. 4, it will be noted that the lower ends of the frames 22 and 23 are tapered as indicated at 25, and extending across the tapered ends are the transverse bars 26. When using the hanger 21 for supporting trousers, the 30 same are suspended by the cuffs thereof and said cuffs are received within the enlarged area 27 as defined by the cross bars 24. The reduced end 25 and transverse bars 26 engage beneath the edge of the cuff so as to doubly assure the 35 retention of the trousers within the hanger. It will be readily noted that should the gripping of the trousers be reduced at the area 27, the reduced portion 25 and bars 26 will prevent the total dislodgment of the trousers from the 40 hanger.

45 For locking the members 22 and 23 together there is provided on each of the U-shaped arms 19 a slidably ring 28 movable thereon to increase or decrease the tension of the members in the 45 usual manner of trouser hangers. A series of projections 29 are provided on the arms 19 for engagement with the ring 28 to retain the same in its adjusted position.

50 From the above description it will be readily apparent that there is provided a garment hanger adapted to support a coat and trousers thereon. The coat supporting arms are adapted to be swung upwardly when positioning the trousers within its hanger 21. After positioning the 55

trousers the arms 10 and 11 are swung downwardly to support the coat and by means of the ends 20 said arms are frictionally held.

To accommodate the bulging seams in the cuffs 5 of trousers, the transverse bars 24 are pressed outwardly as indicated at 30 in Fig. 3 of the drawing.

In Figs. 5 and 6 there is disposed a modified form of the invention which is directed particularly to a trouser hanger in which the supporting members are formed preferably of sheet metal. The complementary members 31 and 32 are of substantially the same size as the trouser cuffs and have attached thereto arms 33 which extend upwardly and converge into a suspending hook 34. The members 31 and 32 are compressed by means of the ring 35 slideable on the arms 33 in the manner previously described. Referring to Fig. 6, it will be noted that the ends of the members 31 and 32 converge inwardly to conform to the shape of the cuffs and the portions 36 will engage beneath the cuff to assure its support.

In Figs. 7 and 8 there is disclosed the second modified form of the invention in which the arms 37 extend downwardly thru the cuff-engaging portion 38 and are bent to form complementary members adapted to fit beneath the edge of the cuff of the trousers. As in the other forms of the invention, these loop-shaped ends 39 serve as a secondary means for supporting the trousers and to prevent the same from becoming totally dislodged even tho the clamps 38 become loosened.

It is to be understood that this improvement is capable of extended application and is not con-

fined to the exact showing of the drawing nor to the precise construction described and, therefore, such changes and modifications may be made therein as do not affect the spirit of the invention nor exceed the scope thereof as expressed in the appended claims. 5

What is claimed as new is:

1. In a trousers hanger, suspension members movable toward and away from each other, a plurality of sets of cooperative clamping members carried by said suspension members respectively to clamp the cuff ends of trousers therebetween, one of said sets of clamping members having portions which engage beneath the cuffs, while the cuffs are pressed between another set of clamping members, to aid in supporting the trousers, and means which cooperates with said suspension members to retain all of said sets of clamping members in clamping engagement with the cuff ends. 10

2. In a trousers hanger, a plurality of sets of cooperative clamping members for clamping therebetween the cuff ends of trousers, a first set of members having an offset formation near the center thereof adapted to accommodate seam portions of said cuffs, and a second set of clamping members carried on said first set and having inwardly directed portions adapted to engage beneath the cuffs while said cuff ends are pressed between said first set of clamping members, and means adapted to retain all of said sets of members in clamping engagement with said cuff ends. 15 20 25 30
